MACHINE FOR COLD-DRAWING BAR STOCK

Phillip C. Vetter, Trenton, Mich., assignor to
Great Lakes Steel Corporation, Ecorse, Mich.,
a corporation of Michigan

Application October 9, 1944, Serial No. 557,906

2 Claims. (Cl. 205—24)

1

The invention relates to the cold drawing of bar stock and has for its principal object the obtaining of a construction of machine capable of high production.

More particularly it is an object to facilitate the exchanging of dies and other parts by a change in the work to be performed and to thereby minimize the time the machine is out of action.

It is a further object to obtain other advantageous features and with these objects in view the invention consists in the construction as hereinafter set forth:

In the drawings:

Fig. 1 is a side elevation of my improved machine;

Fig. 2 is a plan view thereof;

Figs. 3 and 3A are respectively the righthand and lefthand portion of an enlarged vertical section on line 3—3; Fig. 2;

Fig. 4 is a cross section on line 4—4; Fig. 2;

Fig. 5 is a cross section on line 5—5, Fig. 2; and

Fig. 6 is a longitudinal section showing the carriage propelling screw and driving mechanism therefor.

As illustrated in Figs. 1 and 2, my improved machine comprises a frame or draw bench including bed members A and B at opposite ends thereof and laterally spaced longitudinally extending beams C, C' supported upon and extending between said bed members. Travelingly mounted on the frame is a push carriage D and a draw carriage E. There is also a die mounting F fixedly secured to the frame intermediate the carriages D and E. The carriage D is reciprocated by hydraulic piston motors G, G' mounted on the bed A on opposite sides of the center thereof. The piston rods G² of these hydraulic motors are directly connected to brackets D² on opposite sides of the carriage D which latter is slidable in ways D² mounted on the bed A. The carriage E is supported on wheels E' which travel along guide rails H and H' mounted on the beams C, C'. The actuating mechanism for this carriage comprises a pair of revoluble screw threaded rods I, I' engaging correspondingly threaded bearings I² located in pockets on opposite sides of said carriage. The rods are journaled at their opposite ends in roller bearings I³ and are revolved by a drive mechanism later to be described.

The function of the carriage D is to first engage the work bar and to advance the same through and beyond the die a sufficient distance for engagement with the carriage E. From that

2

point on the bar is drawn by the carriage E until it passes completely through the die. Both carriages D and E are, therefore, provided with work grippers and to increase the capacity of the machine, each carriage has a plurality of such grippers arranged side by side for simultaneously advancing parallelly arranged work bars through a corresponding number of dies. Each work gripper J comprises a pair of jaws J' fashioned in their gripping faces to correspond to the work bar to be engaged. The outer faces J² of these jaws are oppositely inclined with respect to the longitudinal axis of the bar and each face engages a series of rollers J³ arranged between the same and a parallel race member J⁴. Springs J⁵ bearing against the large end of each jaw urges it in a direction to effect a radial inward movement against the bar. The jaws J' are flared at their small ends to receive the end of a work bar which, when moved in this direction, will shift said jaws longitudinally against the pressure of the springs J⁵ and will radially expand them to receive the bar. As the jaws J' must fit the work bar which is being fed, it is necessary to exchange said jaws whenever a change is made in the size of the work. This is accomplished by mounting each gripper unit in a holder K which latter is removably mounted in the carriage D or E. To this end each carriage is formed with a series of parallelly arranged pockets K¹, K², K³ open at their upper ends and each of a size to receive the holder K. The front and rear walls of each pocket are apertured in alignment with corresponding apertures in the holder K and with the axis of the gripper J. K⁴ and K⁵ are exchangeable guide bushings inserted in these apertures and of an internal diameter corresponding to the external diameter of the work. The bushing K⁵ extends through both the aperture in the wall of the pocket and that in the holder K and forms a lock for the holder in its pocket. The bushing K⁴, however, is only in the holder K and does not interfere with the insertion of withdrawal of the latter from the pocket. Thus, whenever the gripper jaws are to be exchanged, this may be accomplished by first removing the bushing K⁵ and then lifting the holder K out of the pocket together with the gripper assembly arranged therein as a unit. The gripper assembly including the jaws J', rollers J³ and race members J⁴ are retained in the holder K by plates J⁶ on opposite sides thereof. These plates are secured by screws J⁷ and by detaching one of the plates, the jaws

may be removed and replaced by other jaws of the proper size.

The die mounting F is formed by a pair of posts extending upward from the bed A on opposite sides thereof. The inner faces of these posts are grooved at F' to receive tongues F² on opposite sides of a removable die holder L. The latter is provided with a series of pockets L' for receiving the dies L² which will be respectively positioned in alignment with the grippers J in the carriages D and E. Preferably each die L² is mounted in a semi-spherical member L³ and the pocket L' is of corresponding spherical shape to receive this member. This permits of accurately aligning each die by rotary adjustment of the member L³ in the pocket L' which is accomplished by set screws L⁴. These set screws threadedly engage a cover plate L⁵ detachably secured to the holder L and closing the pocket L'. Thus, whenever dies are to be exchanged, the holder L may be lifted out of engagement with the grooves F' in the posts F to remove the holder and die as a unit after which the plate L⁵ is detached, the die L² removed and replaced by an exchange die. This is properly aligned by adjustment of the screws L⁴ after which the holder L is replaced.

It has been stated that the carriage D is reciprocated by the hydraulic motors G and G'. Also the construction of the gripper J is such that it will seize the work during the forward advancement of the carriage and will release it during the return movement. However, it is necessary to hold the work from being frictionally moved rearward with the carriage and this is accomplished by a one-way clutch M mounted on the bed A. The clutch M includes a stationary jaw member M' mounted in a frame M² while a movable jaw member M³ is pivotally attached to a toggle lever M⁴. A spring M⁵ urges the toggle lever in a direction counter to the advancement of the work and this movement of the toggle forces the jaw M³ towards the jaw M'. Thus, while the stock bar is free to move through the clutch M in the direction of forward advancement of the carriage D, it will be held by said clutch from any movement in the reverse direction.

My improved machine has a number of auxiliary devices and specific elements other than those thus far described. However, as these form no part of the instant invention, it is not necessary that they should be described in detail. In general, the screw-threaded rods I and I' are rotated by a rotary hydraulic motor N through the medium of a gear transmission mechanism not shown. The hydraulic motor N and the motors G and G' are controlled by suitable valves and a timing mechanism which causes the carriage D to reciprocate a predetermined number of times, while the motor N is stationary. The motors G, G' then remain stationary while the motor N operates to rotate the screws I, I' and advance the carriage E. During the operation of the reciprocating carriage D, the stock bars are

pushed forward step by step by the grippers J through the dies L² and into a position for engagement with the grippers J of the carriage E. The latter carriage is then advanced until the bars are drawn completely through the dies.

In practical manufacture it is frequently necessary to adjust the machine for operation on different sizes of stock bars. It is, therefore, obvious that the output of the machine will be limited by the length of time required for making such exchanges. I have reduced this time to the minimum by a construction which permits of very quickly removing and replacing the holders for both the grippers and the dies; also, by the provision of spare holders so that while the machine is in operation with one set of grippers and dies, exchange grippers and dies may be engaged with a set of spare holders. Thus, when the holders of one set are removed from the machine, replacement by the substitute holders may be quickly effected.

What I claim as my invention is:

1. In a draw bench, a frame, a work advancing carriage mounted for travel on the frame, said carriage having a pocket open at its upper end and having an aperture opening into the pocket, a work gripper, a holder containing said work gripper, said holder being insertable into and removable from said pocket through the open upper end and said holder including an aperture aligned with the carriage aperture, and a work guide bushing removably mounted in the aligned apertures in said carriage and holder to lock the holder in the carriage pocket.
2. In a draw bench, a frame, a work advancing carriage mounted for travel on the frame, said carriage having a pocket open at its upper end and having an aperture opening into the pocket, a work gripper, a holder containing said work gripper, said holder being insertable into and removable from said pocket through the open upper end and said holder including an aperture aligned with the carriage aperture, a work guide bushing removably mounted in the aligned apertures in said carriage and holder to lock the holder in the carriage pocket, and a retainer for said bushing in its locking position.

PHILLIP C. VETTER.
